GUN

Gladeon M. Barnes, United States Army,
Hastings, Mich.

Application May 31, 1933, Serial No. 673,661

10 Claims. (Cl. 89—43)

(Granted under the act of March 3, 1883, as
amended April 30, 1928; 370 O. G. 757)

The invention described herein may be manufactured and used by or for the Government for governmental purposes, without the payment to me of any royalty thereon.

5 The subject of this invention is a gun and is an improvement on the gun shown in Patent No. 1,845,217 of February 16, 1932.

The system of controlling the movement of a gun as proposed in the patent contemplates the 10 reversal of a portion of the gases of discharge and their collection for utilization by compressive action and reaction to retard the gun in recoil and restore it to battery.

15 The present gun involves the same principles embodied in the patent and the improvements are directed to mechanical arrangements in order to simplify the mechanism and reduce the number of parts and the cost of manufacture.

With the foregoing and other objects in view, 20 the invention resides in the novel arrangement and combination of parts and in the details of construction hereinafter described and claimed, it being understood that changes in the precise embodiment of the invention herein disclosed 25 may be made within the scope of what is claimed without departing from the spirit of the invention.

A practical embodiment of the invention is 30 illustrated in the accompanying drawings, wherein:

Fig. 1 is a view in side elevation of the improved gun.

Fig. 2 is a longitudinal sectional view of the muzzle.

35 Figs. 3 and 4 are sectional views on the corresponding lines of Fig. 2.

Fig. 5 is an enlarged longitudinal sectional view through the piston head.

40 Figs. 6 and 7 are sectional views on the corresponding lines of Fig. 5.

Figs. 8, 9 and 10 are views in elevation of elements of the valves in the piston head.

45 Fig. 11 is a longitudinal sectional view of the rear end of the piston and is a continuation of Fig. 5.

Fig. 12 is a sectional view on the line 12—12 of Fig. 17.

Fig. 13 is a sectional view on the line 13—13 of Fig. 11.

50 Fig. 14 is a plan view showing the control leading from the cradle.

Fig. 15 is a sectional view on the line 15—15 of Fig. 17.

55 Figs. 16 and 17 are views on the corresponding lines of Fig. 15.

Referring to Fig. 1, there is shown a gun barrel 5 reciprocally mounted in a cradle 6 having trunnions 7 at its rear end whereby it is supported for movement in elevation on a carriage 6a.

60 Secured on the muzzle of the gun barrel is a

combined brake and gas collector including a casing 8 (Fig. 2) spaced radially from the end portion of the barrel and carrying vanes 9 for deflecting gases rearwardly. A valve casing 10 integral with the casing 8 carries a valve block 11 that is in fluid communication with the casing 8 through the inlet passage 12. A valve 13 slidably mounted in the block 11 has a head 14 engageable with the seat 15.

5 The outer portion of the valve block forms a 10 casing 16 for housing a nut 17 threaded on the valve. The nut is held against rotation by means of a pin 18 fixed in the casing 16 and it is normally held in rearmost position against the shoulder 19 by means of a spring 20 seated on a plate 21 closing the front end of the casing 16. A squared stem 22 on the valve is slidable through the hub of a gear wheel 23 housed between the plate 21 and a plate 24.

A cylinder 25 threaded to the 20 valve casing 10 is similarly secured at its rear end to a stuffing box 26 (Fig. 5). The stuffing box is mounted in a hanger 27 fixed to the gun barrel (Fig. 1) and is made fast to the hanger by means of a collar 28 on its forward end and a 25 retaining ring 29 on its rear end.

The piston for the cylinder 25 comprises a piston head 30 and a piston rod formed of connected tubes 31 and 32, (Figs. 5 and 11) the rear tube 32 having a greater cross-sectional area 30 than the front tube 31. The rear tube is secured to a block 33 that is supported by trunnions 34 in the cradle (Fig. 1).

The piston head 30 (Fig. 5) is formed with a 35 chamber 35 and with a plurality of longitudinal passages 36 establishing communication between the chamber and the tube 31. A sleeve 37 secured to the front end of the piston head is formed with a valve seat 38 on its inner or rear end. A valve 39 positioned in the chamber 35 and adapted to 40 engage the valve seat 38 is supported by means of guides 40 integral with its forward end and engaging the interior of the sleeve 37.

A nut 41 on the forward extremity of the valve has a key 42 fitting in a slot 43 in the sleeve 37 and holding the valve against rotation. Gases from the cylinder 25 flow past the guides 40 and move the valve 39 rearwardly off of the seat 38 until the valve is arrested by contacting the rear wall of the chamber 35.

45 The forward portion of the valve 39 is provided with an axial passage 44 communicating with radial passages 45 in rear of the valve face 39a. A valve 46 threaded in the valve 39 is movable across the inner ends of the radial passages 45. The valve 46 has a pair of lugs 47 engageable in slots 58 in the forward end of a sleeve wrench 48 which is rotated by an outer tube 49 extending axially through the tubes 31 and 32 and the trunnion block 33.

Within the front end of the sleeve wrench 48 is a hollow valve seat member 50 which is held against rotation relative to wrench 48 by means of a threaded connection 50a and has a seat 51 on its rear end. A valve 52 for regulating the opening at the seat extends through the hollow member 50 and has a stem 53 threaded in a nut 50b having an axially slidble connection with the forward end of the member 50. The valve 52 is rotated by a tube 54 within the tube 49. The forward end of the tube 54 is closed by a plug 55. A port 56 provided in the wrench 48 in front of the tube 54 and in rear of the valve 52 leads to an inclined passage 57 in the piston head 30. This passage conducts gases to the space between the rear end of the piston head and the stuffing box 26. The gases are admitted to the hollow member 50 through the slots 58 in the sleeve wrench 48 and ports 59 in the valve 39. The outer tube 49 (Fig. 11) is rotated by means of a disc 60 on its rear end and the inner tube 54 is rotated by means of a disc 61, having an annular row of teeth 61a which selectively engage a finger 62a on a lock nut 62 squared on the tube 54. A spring 63 and sleeve 64 confined between the discs maintain the outer tube against the rear face of the block and insures its engagement with the sleeve wrench. A cover 65 threaded to the block houses the discs. The positions of the discs and the corresponding adjustments of their valves is indicated in any appropriate manner.

The trunnion block 33 contains an inclined passage 66 establishing communication between the tube 32 and a small tube 67 attached to the rear face of the block 33 and to a valve block 68 (Fig. 15) at the rear end of the cradle. The tube 67 leads to a passage 69 in the block 68.

A valve casing 70 in the block 68 has its forward end disposed in a cylinder 71 containing lubricant 72. An aperture 73 in the casing admits the lubricant which may flow into a chamber 74 past a valve 75 normally held open by a spring 76. A plug 77 closing the rear end of the casing 70 has an axial passage 78 in which the stem 79 on the rear end of the valve is insertable. A passage 80 in the stem 79 establishes fluid communication between the passage 78 and the chamber 74 when the valve is closed but not when it is open. The passage 78 is open to the passage 69 in the valve block 68 by a connecting passage 78a leading through the plug and casing whereby gas is conducted to the chamber 74.

A port 81 in the casing 70 in front of the plug 77 admits lubricant from the chamber 74 to a vertical passage 82 (Fig. 16) in the valve block. The passage 82 leads to a small tube 83 parallel to the tube 67 and by means of a lateral passage 84 it also leads to the space between a fixed outer tube 85 and an inner tube 86 (Fig. 12) the latter moving with the gun and associated with the valve casing 10 at the muzzle of the gun barrel. A ball valve 87 is placed in the passage 82.

The lubricant forced through the tube 83 enters a passage 88 (Fig. 11) in the trunnion block 33 and is conducted to a peripheral groove 89 between packing rings 49a on the tube 49. The groove is in communication with the interior of the tube 54 through a port 90. At the front end 70 of the tube 54 (Fig. 5) a port 91 conducts the lubricant to a peripheral groove 92 between packing 54a, then by way of port 93 in the sleeve wrench 48 to a groove 94 between packings 48a and then by way of port 95 in the piston head 75 to a groove 96 between packings 30a.

The outer tube 85 terminates forwardly in a shaft 97 (Fig. 11) that is internally round and externally square over its rear portion and includes a journal 98 in the hanger 27 (Fig. 5) and a journal 99 in the valve casing 10 (Fig. 2). The squared rear end of the shaft 97 is slidble in a gear 100 (Fig. 11) carried in a hanger 101 that is integral with a ring 102 connecting the piston rod tubes 31 and 32. The front end of the tube 85 forms a bearing for the inner tube 86 and the latter is accordingly provided with a port 103 whereby it receives the lubricant from the space between the tubes.

A port 104 (Fig. 5) in the inner tube delivers the lubricant through a port 105 in the journal 98, a port 106 in the hanger 27 and a port 107 in the stuffing box 26 which leads to a groove 108 between the packings 26a of the stuffing box.

A port 109 (Fig. 2) in the inner tube delivers the lubricant through a port 110 in the journal 99, a port 111 in the valve casing 10, a peripheral groove 112 and passage 113 in the valve block 11, which passage leads to the packing 13a of the valve 13.

Referring to Fig. 2, a gear 114 on the front end of the shaft 97 meshes with the gear 23. The gear 100 (Fig. 14) on the rear end of the shaft meshes with a gearing 115 driven by a shaft 116 carried by the cradle. The shaft 116 is driven by means of bevel gearing 117 and spur gearing 118 which includes a pinion 119 meshing with an arcuate rack 120 fixed to the top carriage of the gun mount. As the cradle is moved in elevation and depression the shaft 97 is rotated and controls the amount of opening of the valve 13.

In operation when the gun is fired, a portion of the rapidly expanding gases of discharge will be deflected by the vanes 9 of the muzzle brake and delivered past the valve 13 to the cylinder 25. A part of the energy of recoil is counteracted by the forward pressure exerted on the vanes. The gases delivered to the cylinder 25 open the valve 39 in the piston head and flow freely through the longitudinal passages 36 into the piston rod 31-32 and also past the valve 52 and through the passage 57 to the space between the piston head and stuffing box.

When the pressure in the cylinder 25 and piston rod 31-32 exceeds the rapidly decreasing pressure in the bore of the gun the valve 13 is closed. The gases confined in the cylinder and piston rod will be compressed as the forward end of the cylinder approaches the stationary piston head and will act to yieldingly check the recoil of the gun, and then move the gun in counterrecoil.

During the counterrecoil stroke of the gun the volume of the cylinder 25 is increasing and the pressure therein is correspondingly decreasing so that it is less than the pressure in rear of the piston head. As a consequence the gases flow forwardly through the passages 36 close the valve 39, and taking the path through the radial passages 45 and axial passage 44 in the valve 39 act on the front end of the cylinder 25 to move the gun into battery. When the cylinder 25 is fully forward a vent 121 (Fig. 5) in its wall is clear of the piston head and enables the gases to flow to atmosphere.

During the counterrecoil stroke, the stuffing box at the rear of the cylinder 25 moves forwardly towards the piston head and forces the gas through an exhaust valve (not shown). The compression of this portion of the gas contained

in the system checks the velocity of the counter-recoiling parts and eases the gun into battery.

The length of recoil is controlled by the degree of opening of the valve 13 which is operated upon 5 movement of the cradle in elevation of depression. The length of recoil can be additionally shortened by reducing the initial gas volume through the insertion of liners in the piston rod 31-32.

10 The velocity of counterrecoil is controlled by adjustment of the valve 46.

The employment of a portion of the gas as a pressure medium to distribute a lubricant to working surfaces and to points requiring a fluid 15 seal has been made clear in the detailed description.

The mechanism 122 (Fig. 1) for holding the gun in battery forms no part of the present invention and is similar to that shown in my prior 20 patents.

I claim:

1. In a gun, a cradle, a gun barrel reciprocally mounted on the cradle, a cylinder carried by the barrel, means for conducting gases of discharge 25 from the gun barrel into the front end of the cylinder, a stuffing box on the rear end of the cylinder, a piston head in the cylinder, a tubular piston rod secured to the piston head, means for trunnioning the rear end of the piston rod on the 30 cradle, a valve in the piston head freely admitting passage of gas into the piston rod and throttling return of the gas, and a valved passage in the piston head for conducting gas to the space between the piston head and stuffing box.

35 2. In a gun, a cradle, a gun barrel reciprocally mounted on the cradle, a cylinder carried by the barrel, means for conducting gases of discharge from the barrel into the front end of the cylinder, a piston head in the cylinder, a tubular piston rod secured to the piston head and cradle, and a valve 40 in the piston head freely admitting gases into the piston rod and throttling return of the gas.

45 3. In a gun, a cradle, a gun barrel reciprocally mounted on the cradle, a cylinder carried by the barrel, means for conducting gases of discharge from the barrel into the front end of the cylinder, a piston head in the cylinder, a piston rod secured to the piston head and trunnioned in the cradle.

50 4. In a gun, a cradle, a gun barrel reciprocally mounted on the cradle, a cylinder carried by the barrel, means for conducting gases of discharge from the gun barrel into the cylinder, a stuffing box on the rear end of the cylinder, a piston head in the cylinder, a piston rod passing through the stuffing box and means for admitting gas through the piston head to the space between the piston rod and cylinder for compressive action on counterrecoil of the cylinder.

55 5. In a gun, a barrel mounted to recoil and counterrecoil, a muzzle brake on the barrel, a valve casing associated with the brake and receiving therefrom a portion of the gases of discharge, a valve block in the casing, a valve slidably mounted in the block, a nut threaded on the stem of the valve, means for holding the nut against rotation, a spring normally holding the nut against the block, means for rotating the valve, and a recoil mechanism utilizing the gas received past the valve for checking recoil and restoring the barrel into battery.

60 6. In a reciprocating gun, a cylinder movable with the gun, means for conducting gases of dis-

charge from the gun to cylinder, a tubular piston rod stationary relative to the cylinder, a piston head in the cylinder formed with a valve chamber having fluid communication with the cylinder and piston rod, a valve mounted in the chamber and movable to interrupt communication from the chamber to the cylinder, a passage in the valve for establishing communication between the chamber and cylinder when the valve is closed, a throttling valve for said passage, an outer tube 10 extending through the piston rod for adjusting the throttling valve, a passage in the piston head for conducting gas from the chamber to the space between the piston rod and cylinder, a valve for regulating flow of the gas to said passage, and a tube within the outer tube for adjusting said valve. 15

7. In a reciprocating gun, a cylinder movable with the gun, means for conducting gases of discharge from the gun to cylinder, a tubular piston rod stationary relative to the cylinder, a piston 20 head in the cylinder formed with a valve chamber having fluid communication with the cylinder and piston rod, a valve mounted in the chamber and movable to interrupt communication from the chamber to the cylinder, a passage in the valve 25 for establishing communication between the chamber and cylinder when the valve is closed, a throttling valve for said passage, a tube extending through the piston rod for adjusting the throttling valve. 30

8. In a gun, a reciprocating barrel, a cylinder having a stuffing box and movable with the barrel, said cylinder receiving gases of discharge from the barrel, a valve regulating the flow of gas, a piston head in the cylinder, a piston rod receiving gas 35 from the cylinder through the piston head, a tube in the piston rod leading to the piston head, a stationary lubricant reservoir on the gun and including a valved chamber for trapping a predetermined quantity of lubricant, means for conducting gas from the piston rod to the valved chamber to expel the lubricant therefrom, a lubricant passage leading from the valved chamber to the tube in the piston rod, and a lubricant passage leading to the stuffing box of the cylinder and to the valve regulating flow of gas into the cylinder. 40

9. In a gun, a reciprocating barrel, a cylinder having a stuffing box and movable with the barrel, said cylinder receiving gases of discharge from the barrel, a valve regulating the flow of gas, a piston head in the cylinder, a piston rod receiving gas from the cylinder through the piston head, a stationary lubricant reservoir on the gun and including a valved chamber for trapping a predetermined quantity of lubricant, means for conducting gas from the piston rod to the valved chamber to expel the lubricant therefrom, and a lubricant passage leading to the stuffing box of the cylinder and to the valve regulating flow of gas into the cylinder. 50

10. In a gun, a support, a cradle trunnioned on the support, a gun reciprocally mounted on the cradle, a recoil mechanism utilizing the compressive action and reaction of the gases of discharge to check recoil and restore the gun to battery, a gas passage leading from the gun to the recoil mechanism, a valve in said passage, an arcuate rack fixed to the support, a pinion on the cradle meshing with the rack, and means for transmitting the motion of the pinion to the valve. 65

70 GLADEON M. BARNES.
